The ornamental design for a holder for a locating device, as shown and described.

DESCRIPTION

FIG. 1 is a front, side perspective view of a holder for a locating device showing our design;

FIG. 2 is a rear, side perspective view thereof;

FIG. 3 is a front elevation view thereof;

FIG. 4 is a rear elevation view thereof;

FIG. 5 is a side elevation view thereof;

FIG. 6 is an opposite side elevation view thereof;

FIG. 7 is a top view thereof;

FIG. 8 is a bottom view thereof;

FIG. 9 is a top perspective environmental view showing the holder for a locating device in an example use;

FIG. 10 is a top perspective environmental view showing the holder for a locating device in another example use, on a collar of an animal;

FIG. 11 is a front, side perspective view of another embodiment of a holder for a locating device showing our design;

FIG. 12 is a rear, side perspective view thereof;

FIG. 13 is a front elevation view thereof;

FIG. 14 is a rear elevation view thereof;

FIG. 15 is a side elevation view thereof;

FIG. 16 is an opposite side elevation view thereof;

FIG. 17 is a top view thereof;

FIG. 18 is a bottom view thereof;

FIG. 19 is a top perspective environmental view showing the holder for a locating device in an example use; and,

FIG. 20 is a top perspective environmental view showing the holder for a locating device in another example use on a collar of an animal.

The broken lines shown herein that are not used for contour or surface shading, represent disclaimed portions of the device and/or are for illustrative purposes only and form no part of the claimed design.
